UNITED STATES PATENT OFFICE.

DOCTOR ALONZO YORK, OF DEL RIO, TEXAS.

SAFETY DEVICE DOOR.

Application filed February 11, 1924. Serial No. 692,090.

To all whom it may concern:

Be it known that I, DOCTOR ALONZO YORK, a citizen of the United States, residing at Del Rio, in the county of Val Verde and State of Texas, have invented new and useful Improvements in Safety Device Doors, of which the following is a specification.

This invention relates to improvements in motor vehicles, the general object of the invention being to provide means for preventing a person injuring himself by getting his finger caught between the door and its frame in closing the door.

Another object of the invention is to provide means whereby the attachment will not interfere with the proper operation of the door.

This invention also consists in certain other features of construction and in the combination and arrangement of the several parts, to be hereinafter fully described, illustrated in the accompanying drawing and specifically pointed out in the appended claim.

In describing my invention in detail, reference will be had to the accompanying drawing wherein like characters denote like or corresponding parts throughout the several views, and in which:

Figure 1 is a view of part of an automobile showing the invention in use.

Figure 2 is a section on line 2—2 of Figure 1.

Figure 3 is a section on line 3—3 of Figure 1.

Figure 4 is a sectional view showing the door in open position.

In these views 1 indicates the body of the automobile and 2 the door thereof. In carrying out my invention, I hinge a plate 3 to

the body, as shown at 4, with the plate extending over the junction of the door with the body so as to cover the crack between the door and body when the door is in open position. This plate is movably connected 45 with the door by means of the headed projections 5, which are carried by the door and which extend through the slots 6 in the plate.

From the foregoing it will be seen that 50 the plate will move with the door so that the crack between the door and the body is always covered by the plate, and thus a person is prevented from placing his fingers in the crack and so prevent injury to his fingers when the door is closed. The plate will move with the door and the headed projections 5 and the slots 6 will prevent the plate from interfering with the movement of the door.

It is thought from the foregoing description that the advantages and novel features of my invention will be readily apparent.

I desire it to be understood that I may make changes in the construction and in the 65 combination and arrangement of the several parts, provided that such changes fall within the scope of the appended claim.

Having described the invention, I claim:—

The combination with a door frame and a door hinged thereto, of an elongated plate overlying the confronting rear and adjacent face of the door and frame respectively, having hinged connection with the latter, 75 studs carried by the door and having slideable engagement with the plate, and springs encircling the studs and engaging the plate.

In testimony whereof I affix my signature.

DOCTOR ALONZO YORK.
